FRANK M. STEINER, OF MINNEAPOLIS, MINNESOTA

LAUNDRY-IDENTIFYING DEVICE

Application filed August 14, 1929. Serial No. 385,871.

This invention relates to improvements in laundry marking devices and has for its principal objects to provide a marking device which can be quickly applied to and removed from the goods, and which will not be detached from the goods in the wash, and which is perpetually indelible.

To properly understand the problems of this art, it is necessary to note the devices at present used for marking laundry. What may be aptly referred to as the bane of the laundry man's existence is the disappearance or loss of the laundry identifying means during the laundering period. This loss results either from the detachment of the mark, or from fading of the mark as when produced by so-called indelible ink. For many years, laundry men have been trying to keep their goods permanently marked.

There are a number of different devices or methods used by laundries for marking the fabrics, and none of them are perfectly satisfactory. One method is to mark the customer's initials or account number directly on the goods. This is generally done by the use of a thin so-called indelible ink. Some of these marks remain over a considerable period of time, and others fade out very quickly. The degree of fading depends upon the kind of goods, the kind of ink, and the way in which the fabrics are washed. "Markers" are kept busy inspecting each piece to see if it is properly marked, and it is common practice to line over a mark which has partly faded. In lining over the partly faded identifying characters it is often done so carelessly that the identification is lost in this manner. Faded indicia is hard to read, particularly if numerals are used, and sometimes in retracting, the number is inadvertently changed.

Another method is to stamp the name or initials on the goods with a marking machine, using so-called indelible ink. It is commonly noted that a mark of this kind is not as permanent as one hand-penned. The application by pen seems to obtain a better penetration of the ink.

Another method is to use a cloth-covered metal clip, which clasps over the edge of the

goods and is pinched to cause a frictional engagement. Of course, in using these cloth-covered metal clips it is necessary to place the mark on the cloth by hand as with a pen, and of course there is then the usual objection of fading. Another objection is that the clips come off during the washing operation, and thus the identifying mark is lost. The disengagement of these clips is partly due to the character of the goods, and partly due to the thickness of the goods and the lack of care with which the clips are put on.

In another method, pins are used having numbers punched thereon, one pin being attached to each piece of goods. If the customer, for example, sends in fifty pieces of laundry, pins in like number and each having a different number are pinned one to each piece of goods. However, the pins have to be taken off during the ironing operation to avoid marring of the linen and crushing of the pins and then the pins have to be put on again after ironing. Then the particular batch must be bundled and the pins are again removed and then the bundle wrapped for delivery. The removed pins must be sorted numerically so that they may be conveniently used to mark other batches of wash. These are very time-consuming operations.

Where a linen supply company is supplying wearing apparel and laundering it, it is, of course, necessary to identify each garment. However, for various reasons the marks on these garments have to be changed. For example, the customer may wish to change from one style to another, in which case it is desirable to remove the marks from the discarded style and use these garments in service for another party. In this instance, an identifying mark for the second party will have to take the place of the first mark. It is, therefore, desirable to have a mark which will not only remain attached and be indelible, but which can be attached quickly, as well as removed quickly.

Moreover, laundry and linen supply company customers change from one laundry to another, and for each change the new laundry must place one of their own identifying marks on the goods. For example, in travel-

ing a customer will send his linen to a different laundry where the mark is changed. It is, therefore, evident that it would be highly advantageous if a perpetually indelible mark could be obtained which could be both rapidly applied yet rapidly removed, and which would never become accidentally detached; the present invention provides such a device. Speed is a big factor in marking, and de-marking, inasmuch as there are often as many as twenty-five to fifty thousand pieces handled in a few days.

From the above considerations, it will be evident that laundries have sought in vain for a permanently indelible mark which can be quickly attached and detached, and which will stay put. The present invention contemplates the use of a metal tag having the identifying indicia punched therein, the material of the tag being thin and flexible and of such texture that it can be attached to the goods by stitching, for example machine stitching, including lock and chain stitch. The invention also contemplates the use of a fabric mark in which the indicia is produced by punching to form openings through the material, and in which the material to which the tag is attached and the material of the tag are of different colors to accentuate the outline of the cut-outs. For example, a white fabric marker having the cut-out indicia can be secured to a colored material so that that material will show through the cut-outs to accentuate the mark, by contrast.

Objects, advantages and features of the invention will be further set forth in the description of the drawings, and in said drawings:

Figure 1 is a plan view showing a piece of washable fabric having the thin identifying tag of non-corrodible metal machine stitched thereto, in this instance by applying the stitching marginally;

Figure 2 is a section of Figure 1 further illustrating the device and roughly indicating the relative thicknesses of fabric and tag;

Figure 3 is a view similar to Figure 1 showing a metal tag formed from fine mesh screen and having the identifying indicia formed by punching out portions of the material;

Figure 4 is a section of Figure 3 showing the wire mesh tag applied to the fabric and roughly illustrating the differences in thicknesses between the materials of the tag and goods to which the tag is attached. It will be understood that this difference in thickness ordinarily occurs because it is most desirable that the metal tag have great flexibility;

Figure 5 is a view illustrating a fabric tag in which the indicia are produced by cutting openings, and in which tag and goods are of different colors, to contrast or accentuate the mark;

Figure 6 is a section of Figure 5;

Figure 7 shows a tag of the button type; and

Figure 8 shows a view of the button type tag wherein two sets of thread-receiving openings are used.

In the drawings, the numeral 1 indicates any kind of washable fabric having attached thereto a thin, flexible metal tag 2. The attachment is made by means of machine stitching diagrammatically indicated at 3, the said stitching being marginally applied. Numeral 4 indicates the identifying indicia which may be of any suitable nature and which is in this instance formed by punching, to produce embossed or raised characters. In a device of this kind it is necessary that the metallic material be non-corrodible, and the metals usable are aluminum, copper, metal alloys, galvanized material, and brass. It is, of course, evident that there are other non-corrodible metal alloys which are both cheap and efficient for the purpose herein. There is no intention to be limited to the particular character of the metal as long as it is substantially non-corrodible and sufficiently thin to provide the necessary flexibility. It is desirable that the metal be comparatively soft to permit its attachment by machine stitching, either by overcasting or by lock or chain stitching. However, the metal should be capable of being punched and/or embossed, and sufficiently rigid so that the embossing indicia will not be flattened by pressure during a laundering operation. It is evident that by the use of stitching the tags can be rapidly attached and that the tag can be substantially as rapidly removed by cutting the stitching.

The thicknesses of metal thus far used are within the range of from 1/1000 to 1/2000 of an inch. Although it has not been shown in the drawings, it may be advisable to smooth the edges as by marginal folding, this is particularly desirable when the metal tag is attached to that portion of a collar which engages the neck. It is evident that a mark of this kind is permanent and will not fade out. Goods bearing the tags of the kind described herein have been sent through the laundry on washable goods and have been thoroughly washed and subjected to the chemical action of all the substances ordinarily used in laundering. The goods carrying the tags have been put through various kinds of laundry machines, commonly used in the laundry industry, and the marks have in all instances remained attached and the indicia has remained clear.

Figure 3 illustrates a tag formed from screening 6. A fine mesh "pearl" screening has been used. This is a galvanized product. In this case, the portions of the screen are punched out as at 7 and the openings define the indicia. This is also a quite flexible material and it has been found to give entire satisfaction in the same manner as for the first

described form. A tag of this material is also attached by the use of an ordinary sewing machine stitch indicated at 8, and as in the first case it finds valuable application in laundries that furnish wearing apparel service such as uniforms, and permits rapid attachment and removal of the mark.

It will be understood that the indicia may be produced by embossing, indenting, perforating, stencilling, or by forming the outlines by means of small punchings.

Figure 5 illustrates a modification in which a fabric tag 9 is used. In this instance, the tag has been represented as of white material and portions of the tag have been punched out as at 10 to define the identifying indicia. The tag is attached as in other cases by machine stitching indicated at 11. The fabric 12 in this case is lined for the color blue and a portion of the fabric shows through the punched out openings 10. It will, of course, be understood that any combination of colors can be had, and that the tag 9 may be of a suitable color and the fabric 12 be of white material. In either event, a contrasting mark will be obtained.

In my long experience in this art, no one to my knowledge has ever conceived of using a metal tag, and of attaching it by machine stitching. For many years, many workers, in this line have wished and sought for a permanently indelible laundry mark which could be quickly attached and detached. Therefore, over a long period of years and in this active art, the problem has not, to my knowledge, ever been solved to meet all contingencies.

It will be noted that there are certain metals usable for the purposes herein, which are of a color which contrast with many fabrics, and therefore the color contrast scheme can be carried out by use of a metal tag in the same manner as described for that form of the invention shown in Figures 5 and 6.

Referring to Figure 7 which shows a tag of the button type, numeral 14 indicates the fabric, 15 the metal tag, 16 the stitch-receiving openings and 17 the stitching. This form of tag is secured to the goods by the use of a button sewing machine.

In Figure 8 the button-like tag 20 is elongated and has two pair of thread-receiving openings 21.

53 I claim as my invention:

1. In combination with a piece of fabric, a flexible metal tag which has substantially the same flexibility as the goods and having an identifying mark thereon and marginal machine stitching securing the two together, the marginal stitching being continuous and extending completely around all sides of the tag.

2. In combination with a piece of textile fabric, a metal tag disclosing identifying

means which the laundrying process will not destroy, said tag being of such thinness and softness as to be readily penetrable by the needle of a sewing machine, and machine stitching securing the two together within the margin of the fabric.

3. In combination with a piece of fabric, a metal tag disclosing identifying means which a laundrying process will not destroy, said tag being of such thinness and softness as to be readily penetrable by the needle of a sewing machine, and machine stitching securing the two together, said stitching being applied in a manner to substantially prevent lifting or bending back of the margins of the tag.

In witness whereof, I have hereunto set my hand this 8th day of August, 1929.

FRANK M. STEINER.
